[57] **CLAIM**

The ornamental design for a drawer panel, as shown and described.

DESCRIPTION

FIG. 1 is a perspective view of a drawer panel according to my new design, a drawer being shown in broken lines for purposes of illustration only and forming no part of the claimed design;

FIG. 2 is an enlarged front elevational view thereof;

FIG. 3 is a top plan view of FIG. 2; and

FIG. 4 is a right side elevational view of FIG. 2, the left side being a mirror image;

FIG. 5 is a rear elevational view of FIG. 2; and,

FIG. 6 is a bottom plan view of FIG. 2.
